Primary Examiner — Mary Ann Calabrese(74) *Attorney, Agent, or Firm* — Jose Cherson Weissbrot(57) **CLAIM**

The ornamental design for a manicure table, as shown and described.

DESCRIPTION

FIG. 1 is a top perspective view of a manicure table showing my new design;

FIG. 2 is a bottom perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of the manicure table thereof shown in a stowed position;

FIG. 10 is an enlarged view of the selected portion 10 in FIG. 2;

FIG. 11 is an enlarged view of the selected portion 11 in FIG. 2; and,

FIG. 12 is an enlarged view of the selected portion 12 in FIG. 2.

The broken lines shown in the drawings depict portions of the manicure table that form no part of the claimed design.

1 Claim, 12 Drawing Sheets(56)
